UNITED STATES PATENT OFFICE.

AGNES N. KILMARTIN AND RENA B. MORELAND, OF WASHINGTON, DISTRICT OF COLUMBIA.

FILING SYSTEM.

Application filed October 18, 1928. Serial No. 142,442.

This invention relates to improvements in filing systems, and more particularly to what may be termed a three-stagger guide for a straight alphabetical file.

- 5 The object of this invention is to provide a system of filing for use in condensed form for small capacity, or that may be enlarged into one of very greatly increased capacity, without increased complication.
- 10 A further object being to provide a system that may be increased in capacity as required, and one in which the increase may be made when required and thereby avoid all unnecessary or superfluous guides prior
- 15 to the time that they are needed.

Another object being to provide a system that may be useful in filing numerous forms of data.

Similar numerals indicate corresponding parts in all the figures of the drawings in which:

Fig. 1 is an elevation perspective of a portion of a file case, showing a few of the improved guide cards.

25 Fig. 2 is an elevation of one of the first stagger guide cards.

Figs. 3 and 4 are similar views of a second and third stagger guide card, respectively.

Referring now to the drawings it will be seen that the improved filing system is shown as an alphabetical personnel file and consists of a three-stagger guide system wherein each guide card 5 is provided with a tab 6, 7 or 8 in the first, second or third positions respectively on the upper left edge of the guide card.

On the stagger-one card, tab 6, is placed the first letters of the surname. The stagger-two, tab 7, shows the family group names. The stagger-three, tab 8, indicates the subdivisions of the second, or family groups into alphabetically arranged given names.

Stagger-one, or tabs 6, are a general guide to the alphabetical arrangement of the surnames, up to where a surname that is recognized as a family group is encountered, such as Smith, Jones, Johnson or the like. In the above instances the stagger-two, or tabs 7 would show "Smith", "Jones" or "Johnson" and stagger-three or tabs 8, would show the alphabetical arrangement of the given names of those having the surnames appearing as a family group on stagger-two cards, such as Ben, Carry, or Charles

Smith, or Bell, Curtis, or Susan Jones, etc.

For purposes of illustration, the drawings show the application of the filing system thus described to personnel as listed for instance in a telephone directory, wherein 60 the first stagger-one guide, tab 6, shows "Aar", and the second shows "Abbe".

The above stagger-one guide cards represent all surnames up to, for instance, "Abbott" which will be found on a stagger- 65 two guide card, there being usually, a relatively large number having said surname.

If the surname "Abbott" warrants it numerically, more or less stagger-three guide cards may be used to indicate the alphabetical arrangement of the given names found in the "Abbotts".

The number of guide cards is determined by the volume of papers to be filed.

If the file is small it may be necessary to 75 have only a few stagger-two cards, and then only a few stagger-three guides, under said few stagger-two guides, and should the file be large, the division of the surnames into family groups may be increased and also the 80 number of divisions of the family groups appearing in the stagger-three guides may be increased to meet the requirements. The enlargement may be accomplished originally or after the system has been started.

It may be preferable to have the lettering on stagger-one and stagger-two guide cards different in color from that on the stagger- 85 three guides, to clearly differentiate between the guides carrying the surnames and those indicating given names.

As shown and described this system is applied to personnel filing, it may however, be applied to geographical filing. For instance, if a file of manufacturers of a given 95 article, divided into states, is desired, the stagger-one guides may carry the small state names, the stagger-two guides, the large state names, and the stagger-three guides may indicate the alphabetical arrangement of the 100 firm names.

Again this system is applicable to keeping certain records of a State, by cities for instance, the names of cities being represented on stagger-one guides, except large 105 cities which would be indicated on stagger-two guides, and stagger-three guides indicate the alphabetical arrangement of the data filed.

Briefly, the first stagger represents a gen- 110

eral sub-division of the data of record, the second stagger represents family groups or elected portions of stagger-one data and the third stagger represents a subdivision of the 5 second stagger. Stagger one, two and three represent basic divisions, prominent groups of basic divisions, and subdivisions of said groups.

A filing system of this character may be 10 started with stagger-one cards; as the volume of data requires it, family groups may be expeditiously segregated and stagger-two guides added. After the first enlargement into certain family groups, additional family 15 groups or stagger-two cards may be added at any time without difficulty, and without disturbing the continuity of the system prior to the enlargement. In the same way stagger-three cards may be multiplied by a further subdivision of the stagger-two data. 20

Having fully described our invention what we claim and desire to secure by Letters Patent is:

1. A filing system comprising groups of 25 guide cards having staggered tabs on which are markings representing basic divisions, and prominent divisions of the basic divisions in one color, and subdivisions of said groups in another color.

2. A three-stagger filing system compris-

ing groups of guide cards, one group having tabs arranged adjacent to the upper left corner of the card on which the basic divisions are indicated in one color, another group having tabs located out of line but adjacent to the tabs of the first-named group on which prominent divisions of the first group are indicated in the same color as the first group, and a third group having tabs located out of line but adjacent to the tabs of the first and second-named groups on which subdivisions of the prominent divisions are indicated in a color different from the first and second groups. 35

3. A three-stagger personnel filing system comprising a group of guide cards having tabs extending from the left corner of the card on which basic divisions of surnames are arranged alphabetically, a group of guide cards having tabs adjacent to and out of line with the tabs above referred to, on which family groups are indicated and a group of guide cards having tabs adjacent to and out of line with the tabs above referred to, on which are indicated an alphabetical arrangement of the first given name of the adjacent family group. 40 45 50 55
